UNITED STATES PATENT OFFICE.

MATHIAS R. KONDOFF, OF CYNWYD, PENNSYLVANIA, ASSIGNOR TO BOXBOARD PRODUCTS COMPANY, OF PHILADELPHIA, PENNSYLVANIA, A CORPORATION OF DELAWARE.

TOOL FOR MANIPULATING FASTENERS FOR CONTAINER CLOSURES.

Application filed January 26, 1924. Serial No. 688,739.

My invention is designed to provide means for engaging and securing together transversely disposed members of a fastener for container closures, such fastener preferably comprising a rod secured to walls of the container and extending across the cover, and a keeper extending transversely to and having a looped end for engaging the rod.

In its preferred form my invention comprises a hook for engaging such cross rod and mechanism for moving the hook so as to bring the rod engaged thereby within the loop of the keeper; the keeper being positioned by such mechanism, its looped end elevated to engage the rod by the inclined face of the hook, and the loop closed by a clincher coacting with such inclined face.

The characteristic features and advantages of my invention will more fully appear from the following description of a preferred embodiment thereof and the accompanying drawings in illustration of the same.

In the drawings, Fig. 1 is a side elevation of an instrument embodying my invention shown in position for engaging fastener members attached to a container; Fig. 2 is a side elevation, partly in section, of the instrument shown in Fig. 1 with the parts in the position occupied after the transverse fastener members have been engaged and the looped end of the keeper closed by the clincher; and Fig. 3 is a transverse sectional view on the line 3^x—3^x of Fig. 2.

As illustrated in the drawings, my invention comprises a body or housing 1, having the base 2 containing the slot 3 forming a hook 4 provided with the inclined surfaces 5. A lever 6, journalled in the top of the housing on the pintle 7, has an arm 8 extending through a slot in the base 2 and containing the groove 9. A bifurcated arm 10 extends from the lever transversely to the arm 8, one of the bifurcations having connected therewith a coiled spring 11 anchored to an extension 2' of the base 2 so as to normally retract the arm 8 and spread the members 10 and 2' which form handles for the manipulation of the tool.

A bell crank 12, journalled in the housing 1 intermediate the slot 3 and pintle 7, has a curved arm 13 adapted to lap over the top of the lever 6 and provide a handle for rotating the jaw 14 into clinching relation

with the upper surface of the hook to close 55 the looped end of a keeper resting thereon.

Such instrument is particularly adapted for manipulating a fastener comprising transverse members such as the rod or bar 15 and keeper 16. The rod extends across 60 the top of a closure 17' on a container 17 and has arms 18 extending over the closure rim and hooked in suitably positioned ventilating apertures in the container walls. The keeper 16 is provided with an open end loop 19, which extends over the end of the closure, and is hooked in a suitable ventilating 65 aperture in the end wall.

When the cross bar and keeper hooks have 70 been engaged in the appropriate apertures, my instrument is applied to the container with its base 2 resting upon the cover and the hook 4 in position for engaging the cross bar 15 in the slot 3 and with the keeper 16 disposed in the groove 9 in the arm 8. The 75 application of pressure to the handles formed by the members 10 and 2' causes the arm 8 to bear against the closure rim and moves the housing 1 longitudinally, so that the cross bar 15 is drawn by the hook 4 toward the end of the container and the looped end of the keeper 16 is raised by the inclined surfaces 5 of the hook and its engagement with the cross bar. When the cross bar 15 reaches the open end of the loop 80 it slips into such loop and the handle 13 is then moved to rotate the clincher arm 14 and close the loop, thereby effectually sealing the package. It will be understood that 85 similar fasteners are applied to each end of 90 the container closure.

Having described my invention, I claim:

1. A tool comprising an extended base for engaging a package surface and projecting beyond the edge thereof, a member rigidly connected with said base and projecting outwardly therefrom, a lever pivotally connected with said member adjacent to the top thereof and projecting toward said base and beyond the bottom thereof, and an arm projecting transversely from said lever and forming a handle complementary to the projecting end of said base, said base and lever being provided with fastener and keeper engaging means. 100

2. A tool comprising a base having an extended bearing surface, a lever fulcrumed relatively to said base at a point offset from 105

said bearing surface and perpendicular to a point intermediate its ends, said lever projecting beyond the surface of said base remote from said fulcrum point, said base being adapted for engaging a package surface and having means for engaging a fastener, and said lever being adapted for engaging a package surface transverse to the package surface first named, said base having a handle forming member projecting beyond the package-engaging surface of said lever and complementary to a handle on said lever.

3. An instrument of the character described comprising a fastener-engaging hook, a keeper-positioning device, means for effecting relative movement of said hook and device to engage a fastener and keeper, and a clincher for bending said keeper.

4. An instrument of the character described comprising fastener and keeper engaging members, and a clincher comprising a bell crank having a jaw coacting with one of said members.

5. An instrument of the character described comprising a housing containing a slot forming a fastener-engaging hook and having an extended base forming a handle, and a lever fulcrumed relatively to said

housing and having an arm extending transversely to said base and an arm forming a handle complementary to said handle first named, said hook and lever being moved toward one another when said handles are moved toward one another.

6. An instrument of the character described comprising a housing containing a slot forming a fastener-engaging hook and having an extended base forming a handle, a lever fulcrumed relatively to said housing and having an arm forming a handle complementary to said handle first named and an arm for engaging a container, and a clincher fulcrumed relatively to said housing between said hook and the fulcrum of said lever.

7. An instrument of the character described comprising a body having a hook thereon, and an extension forming a handle, a lever fulcrumed relatively to said body and having an arm containing a groove and an arm forming a handle complementary to said handle first named, and a member having a jaw coacting with said hook.

In testimony whereof I have hereunto set my name this 22nd day of January, 1924.

MATHIAS R. KONDOLF.
